UNITED STATES PATENT OFFICE.

FANNIE L. JACK, OF CHILlicoTHE, OHIO.

DESIGN FOR A HANDLE FOR PANS, &c.

SPECIFICATION forming part of Design No. 26,401, dated December 15, 1896.

Application filed October 7, 1896. Serial No. 608,181. Term of patent 7 years.

To all whom it may concern:

Be it known that I, FANNIE L. JACK, a citizen of the United States of America, residing at Chillicothe, in the county of Ross and State of Ohio, have invented a certain new and useful Design for Detachable Handles, of which the following is a specification, reference being had therein to the accompanying drawing.

This invention relates to new and original designs in handles for frying-pans and the like.

In describing the invention in detail reference is had to the accompanying drawing, forming a part of this specification, and wherein like letters of reference indicate similar parts throughout the figure, which is a perspective view of my design.

The principal features of my design reside in the single strand of wire *a*, entwined together at *b* and carrying a handle *c*. At the other end of the wires the same converge outwardly and upwardly to form hooks *d d*, connected by the transverse rod *e*.

Having fully described my invention, what I claim is—

The design for a handle for pans and the like, substantially as herein shown and described.

In testimony whereof I affix my signature in presence of two witnesses.

FANNIE L. JACK.
